UNITED STATES PATENT OFFICE

SYLVESTER L. JOINER, OF MCGREGOR, TEXAS

REVERSIBLE PLACARD HOLDER FOR TANK CARS

Application filed September 8, 1928. Serial No. 304,666.

This invention relates to a placard holder for tank cars.

It is common practice to use placards on tank cars to display two signals, one to indicate that the tank car is transporting inflammable material and the other signal to indicate that the tank car used for transporting inflammable materials is empty. There are times when the tank cars generally used for

10 transportation of inflammable liquids are used for transporting other lading, such as erosive and other commodities of non-inflammable nature.

At the present time the two signal reversible placard has not been altogether a satisfactory practice or effective when the tank car is used to transport a non-inflammable commodity. This is due to the fact that inspectors and others, upon making the discovery that the tank car is being used to transport non-inflammable materials, and the placard indicating the transportation of inflammable materials and not having been removed from the holder, the inspector has of his own volition removed the placard from its holder to prevent misleading interpretation and has put the placard aside, thereby contenting himself with merely overcoming the display of the misleading signal when non-inflammable materials are being transported. Under such circumstances the inspectors often remove the placard entirely from the tank cars and this has put the owners of the cars to considerable expense to trace the placards, and considerable difficulty has been necessary or experienced in efforts to locate or replace the placards.

It is a comparatively easy matter to misplace or lose the placard when the inspector or other person removes the same from the holder because of the misleading signal or indication.

It is therefore an object of my present invention to provide a placard holder constructed to provide for the display of at least

three signals to indicate that the car is being used for transporting inflammable materials, or is empty, or that the car generally used for the transportation of inflammable material is transporting non-inflammable material, so that the signals will properly enlighten an inspector or others without danger of loss of the placard.

It is another object of the present invention to provide a placard holder embodying among other characteristics, means whereby, when the tank car is converted for use to carry a non-inflammable commodity, the placard may be supported and carried by the placard holder without giving an erroneous indication or signal, and whereby there is no inconvenience placed upon owners of the cars in useless or needless efforts in attempts to trace a missing placard.

It is still further designed to provide a device of the character stated, embodying among other characteristics, means whereby to support a placard in different positions to give three separate and distinct indications and which is readily accessible for positioning the same and without danger of accidental dislodgment of the placard and without possibility of an obstruction being placed along the running board of the car.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is an elevation of the invention illustrating signal indicia of one car and illustrating the placard locked and sealed.

Fig. 2 is a similar view illustrating the invention with the placard unsealed.

Fig. 3 is a view of one face of the placard indicating a third signal.

Fig. 4 is a sectional view on the line 4—4 of Fig. 2.

Fig. 5 is a view looking down upon the connecting web between the leaves of the holder.

Fig. 6 is an enlarged detail sectional view of the locking device for preventing dislodgment of the placard when in the holder and unsealed in the holder.

Fig. 7 is a sectional view through the key 28 illustrating the sealing strip associated therewith when it is desired to maintain the placard sealed in the holder against surreptitious removal by unauthorized persons.

Referring now more particularly to the accompanying drawings the reference character 7 indicates the running board of a tank car upon which my improved placard holder is supported.

A bracket including a foot 8 and an upright 9 is supported on the running board, the foot 9 being preferably bolted or otherwise secured to the underside of the running board 7 and the upright preferably extending upwardly adjacent the outer edge of the running board. The foot of the bracket and the support rising therefrom are preferably composed of strong metal or other suitable material.

The placard holder is indicated generally by the reference character A and consists preferably of sheet metal which may or may not be enameled or which may consist of porcelain or any other suitable material, preferably sheet material, capable of being bent upon itself in a manner to form a substantial web 10 along one inclined edge and provide substantially rectangular shaped spaced front and rear leaves 11 and 12 respectively. The upright 9 of the aforesaid bracket extends upwardly between the leaves and is secured therebetween in any suitable manner, the same being preferably spot welded to the leaves to provide an effective connection between the support and the leaves. The holder is preferably supported on the upright from a corner of the holder and each leaf has three of its edges folded back upon itself to form flanges 13, 14 and 15 which are spaced from the body of the respective leaf to provide guiding and supporting grooves for the placard.

These flanges of each leaf have their adjacent ends spaced to accommodate respective corners of the substantially rectangular shaped placard 16 and the space between the flanges 14 and 15 of each leaf creates a space to give access to an opening 17 formed through both leaves and through the upright 9 of the bracket A for a locking device hereinafter described and to provide a passage to

permit all drainage of water, snow, ice or sleet from the holder.

On the outer face of the front leaf of the holder there is printed or otherwise disposed signaling indicia 18 which is exposed to the view of an inspector or other persons when the placard 16 is disposed against the outer face of the rear leaf, thereby indicating that the car contains non-inflammable liquids or other material. When the placard 16 is removed from its position on the rear leaf of the holder and inserted between the guide and supporting flanges 13, 14 and 15 of the front leaf of the holder the previously exposed signaling indicia on the front leaf of the holder is concealed by the placard which latter then indicates to an inspector or others that the car contains either inflammable liquids or material or that the car is empty, depending upon which face of the placard is exposed to view from the front leaf of the holder. As will be seen in the drawings one face of the placard carries signal indicia indicating that the car carries inflammable material as indicated at 19 while on the other face of the placard there is signal indicia indicating that the car is empty as indicated by the signaling indicia 20.

To maintain the placard in supported position with relation to either leaf of the holder, without necessarily sealing the placard in the holder there is provided a locking device consisting of a head 21 and a shank 22, the latter being slidably supported between the leaves in the aforesaid web 10, which connects the leaves, and which shank is encircled by a helical or other spring 23, confined between the leaves, to normally maintain the head 21 of the locking device in tight engagement with the web 10. The head 21 is bowed intermediate its ends as indicated at 24 and at which point the shank is connected to the head, so that as the head 21 is turned transversely of the web 10 the bowed portion of the head tightly engages the web with the ends of the head overlying the leaves so that the respective end of the head will be engaged by the placard if there be accidental outward movement of the placard incident to a jar or otherwise, and whereby the locking device prevents accidental dislodgment of the placard from operative relation or position with respect to the leaves of the holder. The spring 23 on the shank 22 has a tendency to draw the head 21 downwardly against the web whether the head be disposed longitudinally of the web or crosswise with relation thereto and it will be understood that when the head is disposed longitudinally of the web 10 that clearance is permitted to permit positioning or removal of the placard from either of its positions with relation to the leaves.

To facilitate positioning and removal of the placard from the respective supporting

leaves of the holder the placard is preferably provided with an extension in the form of a lug 25 and which may be readily grasped by the fingers and thumb or otherwise to facilitate especially removal of the placard from the holder.

In order to positively effectually lock the placard in the holder the holder is provided with an aperture 26 at its lowermost corner and this aperture is adapted to fall into registration with the aforesaid openings 17 formed through the leaves of the holder and the upright 9, whether the placard be supported at the front or the rear of the holder, and when this aperture 26 of the placard is brought into registration with the openings 17 the shank 27 of the key 28 is passed through the aligning openings and aperture and a sealing strip 29 is then passed through slots 30 and 31 in the shank 27 and the body of the key 28 and sealed in the usual or any suitable manner to maintain the placard sealed in the holder either at the front or the rear of the holder, against accidental or surreptitious removal by unauthorized persons. This sealed locking key 28 may be maintained against accidental dislocation by means of a chain 32 connected in an eye 33 thereof and with a clevis or other suitable clamp like member 34 embracing the upright of the bracket A. The specific sealing means may be varied according to will and of course for the chain and clevis or clamp like member other means may be employed 35 to secure the sealing key means against accidental loss or displacement.

From the foregoing it will be seen that I have embodied in a single structure a comparatively simple, inexpensive, durable and effective device calculated to give three different signaling indicia characteristics whereby an inspector or others may be accurately notified or warned as to the contents of the tank car, that is to say, whether the tank car is empty or whether it is transporting inflammable or non-inflammable material.

It will also be seen that if a signaling indicia is to the effect that the car contains inflammable material, that in order to indicate that the car carries non-inflammable material it is necessary simply to remove the placard from the front of the holder to the rear thereof when the signaling indicia on the front of the holder indicates that non-inflammable material is in the car and that to indicate that the car is empty it is simply necessary, if the inflammable indicia is indicated on the front of the holder, to remove the placard and reverse it and replace it again on the front leaf of the holder.

What is claimed is:

1. In a device of the character described, a bracket, a placard holder supported on the bracket and including front and rear leaves

connected by a web portion, each leaf being substantially rectangular and having flanges on three sides forming guides and a support for a placard against each leaf, the front leaf carrying signalling indicia, and a placard carrying different signalling indicia on its opposite faces and adapted to be supported interchangeably on the leaves in the respective guides and supports and when supported on the front leaf concealing the signalling indicia on the latter.

2. In a device of the character described, a bracket, a placard holder supported on the bracket and including front and rear leaves connected by a web portion, each leaf being substantially rectangular and having flanges on three sides forming guides and a support for a placard against each leaf, the front leaf carrying signalling indicia, a placard carrying different signalling indicia on its opposite faces and adapted to be supported interchangeably on the leaves in the respective guides and supports and when supported on the front leaf concealing the signalling indicia on the latter, and means for holding the placard against accidental dislodgment from either placard holder.

3. In a device of the character described, a bracket, a placard holder supported on the bracket and including front and rear leaves connected by a web portion, each leaf being substantially rectangular and having flanges on three sides forming guides and a support for a placard against each leaf, the front leaf carrying signalling indicia, a placard carrying different signalling indicia on its opposite faces and adapted to be supported interchangeably on the leaves in the respective guides and supports and when supported on the front leaf concealing the signalling indicia on the latter, means for holding the placard against accidental dislodgment from either placard holder, and another locking means to seal the placard against displacement or surreptitious removal.

4. In a device of the character described, a bracket, a placard holder supported on the bracket and including front and rear spaced leaves connected by a web portion each leaf having supporting flanges for a placard, the front leaf carrying signalling indicia, a placard carrying different signalling indicia on its opposite faces and adapted to be supported interchangeably by the flanges on the leaves and when supported on the front leaf concealing the signalling indicia on the latter, and a spring actuating locking device for releasably locking the placard on either side of the holder.

5. In a device of the character described, a bracket, a placard holder supported on the bracket and including front and rear spaced leaves connected by a web portion, each leaf being substantially rectangular and having flanges on its three sides forming guides and

a support for a placard against each leaf,
the front leaf carrying permanent signalling
indicia, a placard carrying different signal-
ling indicia on opposite faces and adapted to
be supported interchangeably on the leaves
in the respective guides and supports and
when supported on the front leaf concealing
the signalling indicia on the latter, and an
element operable through said web portion
10 and rotatable to releasably lock the placard
on either side of the holder.

In testimony whereof I have hereunto set
my hand.
